(57) **CLAIM**

What is claimed is the ornamental design for a chair, as shown and described.

DESCRIPTION

FIG. 1 is a front perspective view showing the chair of Applicant's invention.

FIG. 2 is a side elevation view of the chair of Applicants' invention.

FIG. 3 is a front elevation of the chair of Applicants' invention.

FIG. 4 is a back elevation of the chair of Applicants' invention.

FIG. 5 is a top view of the chair of Applicants' invention.

FIG. 6 is a bottom view of the chair of Applicants' invention; and,

FIG. 7 is a detailed view showing see-through mesh material as indicated in FIG. 3 by indicia 7.

It is understood that the fragmented mesh material on the backrest would be continuous throughout the circumscribed areas.

The broken line showing of the wall corner is included for the purpose of illustrating environmental structure and forms no part of the claimed design.
